LUMINESCENT SIGN

Harold A. Cline, Dayton, Ohio, assignor of fifty
per cent to Clyde D. Cline, Chicago, Ill.

Application December 22, 1934, Serial No. 758,713

12 Claims. (Cl. 40—130)

This invention relates to improvements in luminescent signs, and, particularly to that type of sign using a luminous gas, such as "neon" contained within a tube or tubes. However it is not intended to limit this invention to the use of "neon" gas, as other types of luminous gas may be used without in any way departing from the spirit of this invention.

Many "neon" signs used principally for advertising are now on the market in general use. However the usual sign of several letters is made by one continuous tube forming the word or words of the sign. In this type of continuous tube it is necessary to "block out" the tubes between the letters and also between the words with an opaque material to separate the letters from each other and to make them readable.

Such types of sign are extremely limited to the specific use for which they are originally made, and for this reason cannot be used very extensively for advertising, since when once formed for a specific use they are absolutely unchangeable. Hence theaters cannot use them in their marquees or canopies, or on building fronts, to advertise the plays or pictures showing in such theaters. This of course is due to the fact that the plays and pictures, especially the latter are usually changed either weekly or semi-weekly. Therefore, it would be very impractical and expensive to have new "neon" signs manufactured for each change of program.

Likewise, merchants cannot use such signs for advertising due to the many various types of articles sold and to constantly changing prices.

It is, therefore, an object of the present invention to provide a "neon" or other luminous gas, type of sign comprising a plurality of interchangeable letters, characters, numbers, hieroglyphics, and non-luminous members, whereby any desired wording or numbering may be readily displayed to advertise whatever a merchant may wish to emphasize, or whatever program a theater manager may wish to get before the public.

It is another object of this invention to make such letters, numbers, characters, hieroglyphics and non-luminous members, of the novel luminous sign, mounted wholly independently one from the other, whereby any one of them may be changed or replaced without effecting any other one.

Another object of this invention is to produce such signs at a comparatively low cost.

Another object of the present invention is to provide the luminous gas tube characters, numbers or letters with a substantial individual car-

rier or support all of which have certain common characteristics thereby rendering them easily shiftable from any one position to any other position to create new and different word displays as the occasion demands.

A further object is to provide such individual carriers in such forms that when they are placed in position in the composite sign, said carriers will display an outline corresponding to the letter, number, or character tube which they support.

A still further object is to provide a main panel or plate for a sign, said panel carrying electrical terminal sockets spaced at regular intervals, and also having a supporting means and a guiding means to receive individual interchangeable letters, numbers, characters, and non-luminous members, the latter wherever necessary to separate words of a sign.

Another object is to provide the above mentioned guiding means with locating means arranged at regular intervals whereby the characters of a sign will always be accurately spaced.

Another object is to provide a novel and positive means for locking the non-luminous member or circuit carrier, and also a positive locating means for said non-luminous member.

Still another object is to provide each terminal socket with a novel cover to protect it from the rain and weather.

Another object is to provide the above mentioned cover with a conducting member to complete the circuit from the character electrodes to the terminal sockets.

A further object of the present invention is to provide a novel sign of the luminous gas type having luminous gas characters mounted wholly independently from each other but being connected in electrical series as they are inserted in position in the sign.

With these and incidental objects in view the invention consists of certain novel features of construction and combinations of parts, the essential elements of which are set forth in appended claims, and a preferred form of embodiment which is hereinafter described with reference to the drawings which accompany and form part of this specification.

Of said drawings:

Fig. 1 is a top plan view of a portion of the novel sign.

Fig. 2 shows in front elevation, two sections of a sign.

Fig. 3 is an edge view of Fig. 2 with certain parts broken away for clearness.

- 25 Figs. 38, 38a and 38b show a front elevation, a side elevation and a top plan view, respectively, of the character representing, and
- 30 Figs. 39, 39a and 39b to Figs. 46, 46a and 46b inclusive, show front elevations, side elevations and top plan views, respectively, of numbers.
- Figs. 47, 47a and 47b inclusive, show a front elevation, a side elevation and a top plan view respectively, of a question mark.

Generally

As stated at the outset this invention is particularly adapted for use by theater owners and merchants to advertise their programs and wares, respectively.

40 The panel carrying the character supports and guiding means is especially constructed so that the characters may be very quickly and easily changed from one position to any other position to form new display matter with the "neon" or other luminous gas characters. The assembled panel is also constructed so that it may be used in the present theater marquees or canopies. Once the panel has been installed, it requires very little time and it is a very simple matter 50 to change the sign to advertise new programs.

As compared with the present signs used by many theaters the words and characters of which signs are formed by electric light bulbs covered with a so called opalite or white glass the present 55 invention is far superior in many respects. Such signs become very hot due to the retained heat from the electric bulbs with the result that many bulbs burn out during the course of a month. The opalite covers do not permit that heat to escape. Moreover such signs are very difficult 60 to change and also require much more time to change than do the characters of the present invention.

Some of the present day theaters have a single 65 panel marquee while others have two, three and four panel marquees. In Figs. 2 and 3 a double panel marquee is represented generally by the dot-and-dash lines, in which double marquee is installed applicant's novel sign comprising panels 70 with their supports and guides for the "neon" or other luminous gas letters and characters.

These panels are so constructed that the letters, characters or non-luminous members can be assembled only in their proper positions 75 pending upon the words to be used in the ad-

vertising display. As the last letter or circuit carrier of a panel is inserted in position the letters in said panel are "lighted" as the last one inserted completes the series circuit.

A transformer supplies the necessary high voltage and high potential energy for each set or unit of letters on each panel. Usually one transformer is used for each panel. The transformer used is merely connected into the standard lighting current on the input side and provides the 10 necessary voltage for the lamps at the output.

Detail description

Panel assembly.—Referring particularly to Figs. 2 and 3, a theater marquee or any other sign holder is represented by the numeral 60, and is shown as supporting a main panel 61 which may be made of steel and insulated from the marquee if desirable or if insurance underwriters require it. The panel may also be made of insulating material if desirable. The size of the panel depends wholly upon the place where it is to be used. The thickness also depends upon the same thing.

Secured to the panel 61 (Figs. 2 to 6) by any suitable means is a channel bar 62 the front side 63 of which forms one side of a guiding channel, the rear side of which is formed by the curved bar 64 secured to the base of the bar 62. This bar 62 acts as a support for the characters. The rear side 65 of the bar 62 provides the means of attachment to the panel 61. The channel bar 62 and the bar 64 extend the full length of the panel 61.

Secured to the panel 61 (Fig. 3) near the top thereof is a channel bar 66 the rear side 67 of which affords the means of securing said bar 66 to said panel 61. The front side 68 of the bar 66 acts as one side of a guiding channel for the letters and characters to be later described. The lower portion of the side 68 is flared to form a guide 69 to aid in the insertion of the letters and characters in the sign. The side 68 and guide 69 also act to conceal certain parts of the letter carriers, so that the latter display an outline corresponding to the letter which they carry. An angle bar 70 secured to the bar 66 forms the rear side of the guiding channel for the letters and characters. The bar 70 is also flared to form a guide 71 to also aid in the insertion of the letters and characters in the sign.

The bar 70 carries studs 72 (Figs. 1 to 3) which are spaced at regular intervals for accurately locating the letters in the sign relatively to each other and also relatively to the electrical sockets 55 to be later described. The channel bar 62 has secured to the base and extending the length thereof, a curved bar 73 (Figs. 2 and 4 to 6) the purpose of which will be later described. The rear side 65 of the bar 62 is provided at regular 60 intervals with notches 74 the function of which will be later described. The channel bars 62 and 66 are connected at their ends by a bar 75 (Figs. 1 and 3) only one of which is shown, the guide 69 being cut away as at 76 to provide clearance 65 for said bar 75.

Terminal socket and cover.—Terminal sockets 85 (Figs. 1 to 6) made preferably of porcelain are carried by the main panel 61, which panel is provided with openings 86 to receive tenon 70 ends 87 of the sockets 85. A shoulder 88 on each socket 85 limits the insertion of the sockets and provides means for gripping clips 89 (Fig. 4) by means of which the sockets 85 may be held in their places.

Each socket 85 has a binding post or terminal bolt 90 (Figs. 1, 3, 4, 5 and 6) secured in place by nuts 91 between which is secured one end of a conductor wire 92. Under the head of the bolt 90 is secured one end of a conductor wire 93 which is connected to a very light conductor spring 94 (Figs. 3 and 6). The conductors 92 electrically connect adjacent pairs of sockets 85.

A cover 95 (Figs. 6 and 10) made of flexible material, such as rubber and having a rolled edge 96 is adapted to be stretched over the tenon end 87 of the socket 85 to prevent rain and moisture from getting inside the socket 85. This cover is however not essential to the proper functioning of this invention and may be omitted if desired. On opposite sides of the center part of the cover 95 are metal disks 97 and 98. These disks are secured to the cover by a rivet 99 or any other suitable means, such as a screw.

The end coil of the spring 94 is in constant contact with the disk 97 and the rivet 99 completes the circuit from the disk 97 to the disk 98. Should the cover 95 not be used then the spring 94, that is, the end coil thereof is directly contacted by the electrodes on the letters and by the contact ends of the circuit carrier or non-luminous member, later described.

When the cover 95 is used, which is preferable on outside signs, then the electrodes on the letters and the contact ends on the circuit carrier contact the disk 98 when said letters and carriers are in positions in the sign. When the cover 95 is stretched over the tenon 87 said cover is flat or straight as shown in Fig. 10, and the end coil of the spring 94 touches the disk 97. However when the letter or circuit carrier is inserted their electrodes and contact members respectively, force the disks 97 and 98 inwardly to the position shown in Figs. 1, 3 and 6 thus stretching the cover 95.

Circuit carrier or non-luminous member.—A circuit carrier, designated generally by the number 100, is shown in detail in Figs. 7 to 9 and in functioning position in the sign in Figs. 1 to 6. This carrier 100 (Figs. 7 to 9) is comprised of a support plate 101, the bottom edge of which may be bevelled or rounded as shown. This plate 101 has openings 102 to reduce the weight. Secured to the plate 101 by screws 103 or any other suitable means is a bar 104 of insulating material such as bakelite. This bar 104 has arms 105 each having either screwed or driven in the ends thereof, a metal contact member 106 preferably with rounded ends. Preferably molded in the bar 104 and its arms 105 is a conductor wire 107 the ends of which are contacted by the ends of the contact members 106 when the latter are either screwed or driven in the ends of the arms 105.

To properly locate the carrier 100 and also to retain it in position in the sign, there is secured to the plate 101 an arm 108 having a downwardly projecting finger 109 adapted to enter the notch 74 in the side 65 of the channel bar 62 behind the bar 73.

To place the carrier 100 in functioning position, the contact members 106 are placed against the disks 98 and the latter are forced inwardly until the plate 101 is above the channel formed by the side 63 and bar 64 at which time the finger 109 is above the notch 74. The carrier is then lowered until the plate 101 rests between the side 63 and bar 64 which lowering simultaneously enters the finger 109 in the notch 74 between the panel 61 and retaining bar 73, the latter acting

to maintain the carrier 100 in its proper circuit completing position shown in Figs. 1 to 6.

Letters, numbers and characters.—The letters of the alphabet are illustrated in Figs. 12, 12a and 12b to 37, 37a and 37b inclusive, the numbers 5 are shown in Figs. 39, 39a and 39b to 46, 46a and 46b inclusive, and some special characters are shown in Figs. 11, 11a, 11b, 38, 38a, 38b, 47, 47a and 47b. While these letters and numbers are shown as of the block type, it is to be clearly 10 understood that other types of letters and numbers may be used without departing from the spirit of this invention.

Each letter is formed by a glass tube 120 (Figs. 12, 12a and 12b) containing neon gas or any other 15 suitable luminous gas. On the ends of each tubular letter, number or character is the usual electrode 121 represented by the enlarged ends. These electrodes carry a conductor wire 122 which extends into the tube to conduct the current to 20 and from the gas to cause the same to become luminous. The ends of the tubes 120 are all terminated exactly the same distance apart and substantially on a line with the lowermost section of the letter, number or character, the only exception in the illustrations being in the hyphen or dash. However the electrode ends of the dash have exactly the respective locations as the electrode ends of the letters and numbers.

Each tube 120 is supported by a plate 123 having the same front elevational outline as its associated character. These support plates 123 have openings 124 located in different positions therein depending upon the shape of the letter or character. In some cases the opposite electrode ends of the tubes 120 naturally fall at the bottoms of the letters, but in others to eliminate many bends and "double tubes" in front of the plates 123 the openings 124 may be at the tops of the letters as shown in Figs. 17 and 20 or said openings may 40 have other convenient locations as shown in Figs. 18, 21, 27, 40, 43 and 46. In some instances there may be need of only a single opening 124, which however is larger to permit the entry of two tubes, 45 as shown in Figs. 2, 3, 26 and 45.

The tubes 120 are retained in position relative to the plates 123 by the usual glass tubes 125 (one only of which is shown in Fig. 12) held to the plate 123 by the usual clip 126 and fastened to the tube 120 by a small wire 127.

The electrode ends 121 are spaced on all letters, numbers, and characters to match the locations of the sockets 85, thus making any letter, number or character interchangeable with any other letter, number or character from that standpoint.

Each letter, number and character plate 123 has a projecting base or bases 128, depending upon the shape of the letter, number or character with which it is associated. This base or these bases 128, when the letter is in position, rests in the channel between the side 63 and bar 64 as shown in Figs. 1 to 3.

Each plate 123 also has an upward projection or arm 129 having a slot 130. This slot 130 in each plate 123 has exactly the same location relative to the bottom of the base or bases 128 and relatively to the vertical center of each plate 123. By this slot 130 which embraces the stud 72 in the bar 70, all letters, numbers and characters are definitely and accurately located relatively to the sockets 85 and relatively to each other, thus producing a sign having evenly spaced characters, letters or numbers. By referring to 75

Figs. 11 to 47 it will be noticed that the arms 129 have various shapes which is controlled by the shape of the associated letter.

All portions of the tubes 120 which are to be 5 "blocked out" with an opaque material are shown shaded by section lines.

The arms 129, when the letters, numbers and characters are in functioning position in the sign are all hidden from view by the sides 68 and 10 guide 69 and the bases 128 are all hidden from view by the side 63 as clearly shown in Figs. 2 and 3. The only exception to the above is in the case of the hyphen. However its long base 128 and long arm 129 may be colored the same 15 as the front of the panel 61 to render them practically invisible.

To remove a letter or character, all that is necessary is to raise the same, clearance being provided in the slot 130, until the base is above 20 the side 63 after which the letter is tilted outwardly at the bottom and slipped down off the stud 72. To insert a letter the arm 129 is inserted between the guides 69 and 71 and the slot 130 slipped over the stud 72. The letter is then 25 raised until the base 129 clears the side 63 at which time the electrodes 121 register with and contact the disks 98 forcing them inwardly to the position shown in Fig. 3. The letter is then lowered until the base 128 rests in the channel 30 between the side 63 and bar 64 by which it is retained in position.

In Figs. 2 and 3 are shown several letters 120 and circuit carriers 100 illustrating the use of the circuit carrier 100 and clearly showing the 35 interchangeability of all letters to form any desired sign for a theater program or to advertise a merchant's wares.

Circuits.—As before stated the letters on each panel are in electrical series and for each panel 40 there is usually provided a transformer, shown only in Fig. 1.

Lines 135 and 136 represent + and - input conductors from the usual house current lines to a transformer 137. Lines 138 and 139 represent 45 the high frequency and high potential energy lines from the transformer to the sockets 85. The previously described conductors 92 conduct the current between pairs of sockets.

In Fig. 1 the circuit is as follows: From one 50 side of the transformer 137, through conductor 138, post 90 on left hand socket 85, spring 94, disks 91, rivet 99, disk 98, letter A electrodes, and tube A to disks, rivet spring and post of next 55 socket 85, through conductor 92, to third socket 85, through carrier 100 to fourth socket 85, next conductor 92, through next four pairs of sockets 85 and tubes 120 in order, to conductor 139 back to opposite side of transformer 137.

While the form of device herein shown is admirably adapted to fulfill the objects primarily stated, it is to be understood that the invention is not limited to the one form of embodiment herein shown, for it is susceptible of embodiment in various forms, all coming within the scope 65 of the claims which follow.

What is claimed is:

1. A sign including a plurality of individually removable and interchangeable luminous gas characters comprised of tubes of luminous gas, the 70 tubes having a pair of terminal electrodes; terminal sockets wired in series; flexible and waterproof covers for said sockets; conductor members in said covers to cooperate with said terminal electrodes and the socket terminals; means for 75 supply the necessary electrical energy; and a de-

vice having a pair of contacts to cooperate with said cover conductor members, the contacts being connected by an invisible conductor, said device being interchangeable with any character in any position to complete the circuit through said conductor members to render the characters luminous. 5

2. A sign including a main member having a plurality of electrical terminal sockets wired in series circuit; means for supplying electrical energy; a plurality of interchangeable luminous gas tube characters having electrodes to cooperate with said sockets to complete the series circuit; carriers for said characters; means interchangeable with any character in any position to 15 complete the series circuit upon the omission of any character in any position, an overhanging channel carried by said main member; character locating means therein; an upturned channel carried by said main member for supporting 20 said character carriers; and a device carried by said upturned channel for retaining said interchangeable means in any position in which it is adapted to be used.

3. A sign including a main member having a 25 plurality of electrical terminal sockets wired in series circuit; means for supplying electrical energy; a plurality of interchangeable luminous gas characters and non-luminous means to complete 30 the series circuit to form the sign as desired; means common to all characters and non-luminous means for supporting the same in definite positions in one direction relative to the terminal sockets; means common to all characters for supporting the same in definite positions in 35 another direction relative to said sockets; and means for retaining said non-luminous means in definite positions in the last named direction relative to said sockets.

4. A sign including a main member having a 40 plurality of electrical terminal sockets wired in series circuit; means for supplying electrical energy; a plurality of interchangeable luminous gas characters and non-luminous means to complete 45 the series circuit to form the sign as desired; means common to all characters and non-luminous means for supporting the same in definite positions in one direction relative to the terminal sockets; means common to all characters for supporting the same in definite positions in another direction relative to said sockets; a projecting member on said non-luminous means; and means carried by the first mentioned common means and cooperating with said projecting member in any 50 position in which said non-luminous means may be used.

5. A sign including a plurality of individually removable and interchangeable luminous gas characters; electrical means including a series circuit for rendering said characters effective; non-luminous means interchangeable with any of said characters and adapted to be used in combination therewith to complete the electrical circuit; supporting means common to said characters and non-luminous means; means for retaining said characters in definite positions relative to each other; and means including a projecting finger on said non-luminous means, a notched member and a bar covering the sides of the notches for 55 retaining said non-luminous means in definite positions relative to said characters.

6. A sign including a plurality of individually removable and interchangeable luminous gas characters; electrical means including a series 70 circuit for rendering said characters effective; non-luminous means interchangeable with any of said characters and adapted to be used in combination therewith to complete the electrical circuit; supporting means common to said characters and non-luminous means; means for retaining said characters in definite positions relative to each other; and means including a projecting finger on said non-luminous means, a notched member and a bar covering the sides of the notches for 75 retaining said non-luminous means in definite positions relative to said characters.

5 circuit for rendering said characters effective; non-luminous means interchangeable with any of said characters and adapted to be used in combination therewith to complete the electrical circuit; carrying means for each character to which each is attached, said carrying means having bases of different formations and having arms of different formations, said arms each having an aperture, the formations of the bases and arms 10 depending upon the formations of the characters which the carrying means has attached to it; guiding means cooperating with said arms; and devices in the guiding means cooperating with the apertures in said arms to maintain all characters 15 in definite positions relatively to each other.

7. A luminous gas sign including a main member having a plurality of electrical terminal sockets; a plurality of individually removable luminous gas characters having electrodes to cooperate with pairs of said sockets; character plates having arms and bases of varying shapes depending upon the characters; a common supporting means for all characters to maintain said characters in definite positions relatively to said sockets and to conceal the bases of the character plates when the characters are in position; and guiding means common to all characters to also maintain said characters in definite positions relatively to 25 said sockets and to conceal the arms of said character plates when said characters are in position.

8. A luminous gas sign including a main member having a plurality of electrical terminal sockets; flexible socket covers having conductor centers; a plurality of individually removable luminous gas characters having electrodes to cooperate with said conductor centers; a channel support carried by said main member and common 30 to all characters to support them in definite positions relatively to said sockets in one direction; a channel guide carried by said main member and common to all characters; and guiding members carried on the channel guide to retain said

characters in definite positions relatively to said sockets in another direction.

9. A luminous gas sign including a main member having a plurality of electrical terminal sockets; a flexible cover for each socket, said cover, having electrical conducting means near the central position thereof; a plurality of individually removable and interchangeable luminous gas characters having electrodes to cooperate with the conducting means of said covers; a device 10 carried by the main member and common to all characters, said device having a channel to support said characters in definite positions in one direction relatively to said sockets; and means carried by the main member to guide said characters in definite positions in another direction 15 relatively to said sockets.

10. A circuit carrier comprising a plate; an insulating member secured thereto, said member having a plurality of projections, said member 20 and projections carrying a continuous electrical conductor; contacts secured in the ends of said projections; means integral with said plate for supporting said carrier; and a device secured to said means for retaining the carrier in position. 25

11. A circuit carrier comprising a plate; an insulating member secured thereto, said member having a plurality of projecting arms, said member and arms carrying a continuous electrical conductor; contacts secured in the ends of said 30 arms; means on the plate for supporting said carrier; and a device projecting laterally from said means and having a finger parallel to said means.

12. A luminescent sign including a plurality of individually removable and interchangeable luminous gas characters; and non-luminous members, said members each including an insulating member carrying a concealed electrical conductor, a pair of contact members, and a supporting plate having secured thereto a laterally and 35 downwardly projecting finger coating with said sign to retain said non-luminous members in their 40 positions.

HAROLD A. CLINE.
